Primary Examiner — Holly E Thurman*Assistant Examiner* — Sharon H Schwartz(74) *Attorney, Agent, or Firm* — Kristin D. Wheeler(57) **CLAIM**

The ornamental design for a shoe as shown and described.

DESCRIPTION

FIG. 1 is a top lateral perspective view of a shoe showing my new design;

FIG. 2 is a top view of the shoe, thereof;

FIG. 3 is a lateral side view of the shoe, thereof;

FIG. 4 is a medial side view of the shoe, thereof;

FIG. 5 is a rear view of the shoe, thereof;

FIG. 6 is a front view of the shoe, thereof;

FIG. 7 is a bottom view of the shoe, thereof;

FIG. 8 is a top lateral perspective view of another embodiment of the shoe showing my new design;

FIG. 9 is a top view of the shoe, of FIG. 8;

FIG. 10 is a lateral side view of the shoe, of FIG. 8;

FIG. 11 is a medial side view of the shoe, of FIG. 8;

FIG. 12 is a rear view of the shoe, FIG. 8;

FIG. 13 is a front view of the shoe, FIG. 8; and,

FIG. 14 is a bottom view of the shoe, FIG. 8.

In FIGS. 1–14, the evenly-spaced broken lines show portions of the shoe that form no part of the claimed design.
